TILLOTSON MANUFACTURING COMPANY, OF TOLEDO, OHIO, A CORPORATION OF
OHIO.

FUEL-MIXER.

1,851,126.

Specification of Letters Patent. Patented Aug. 31, 1920.

Application filed September 5, 1916. Serial No. 118,869.

To all whom it may concern:

Be it known that we, GEORGE F. RITTER and HARRY C. TILLOTSON, citizens of the United States, residing at Toledo, Lucas county, Ohio, have invented new and useful Fuel-Mixers, of which the following is a specification.

This invention relates to improvements in carburetors, and more particularly to carburetors of the type which are provided with a suction-controlled air-intake valve.

The principal object of our invention is to provide a carburetor with a choke tube having side walls formed by flexible reeds which can yield in response to a variation in engine suction to vary the cross section of the choke tube and the volume and velocity of the air flowing past the nozzle. A further object of our invention is to provide an improved automatic suction-controlled air-intake valve. A further object of our invention is to provide a carburetor having a pair of flexible reeds forming a part of the wall of the venturi, said reeds being adapted to yield in response to the engine suction so as to vary the volume and velocity of the air passing through the carburetor, said carburetor being provided with a primary nozzle adjacent the free ends of said reeds and a secondary nozzle disposed behind said primary nozzle. A further object is to provide a carburetor in which the air intake is controlled by the engine suction and in which the parts are so constructed and assembled as to permit of ready accessibility and to reduce the cost of manufacture.

Further objects and objects relating to economies of manufacture and details of construction, will definitely appear from the detailed description to follow.

We accomplish the objects of our invention by the devices and means described in the following specification. Our invention is clearly defined and pointed out in the appended claims.

A structure constituting a preferred embodiment of our invention is illustrated in the accompanying drawing, forming a part of this specification, in which—

Figure 1 is a vertical, sectional view through a carburetor constructed in accordance with our invention.

Fig. 2 is a plan view of the carburetor shown in Fig. 1 with a part of the mixing

chamber wall broken away to show the automatic air-intake valve.

Fig. 3 is a detail, sectional view, taken substantially on the line III—III of Fig. 2.

Fig. 4 is a detail, sectional view, taken substantially on the line IV—IV of Fig. 1.

Fig. 5 is a detail, sectional view, taken substantially on the line V—V of Figs. 1 and 4.

Fig. 6 is a side elevation of the primary nozzle.

Fig. 7 is an enlarged sectional view, similar to Fig. 1, and illustrating more in detail the novel features of the nozzle structure.

Fig. 8 is a horizontal sectional view taken along the line 8—8 of Fig. 7, and illustrating the relative positions of the openings 24 with respect to the nozzle.

Fig. 9 is a horizontal sectional view taken along the line 9—9 of Fig. 7.

Fig. 10 is a vertical sectional view taken through a modified form of primary fuel nozzle.

In the drawings, similar reference numerals refer to similar parts throughout the several views.

Considering the numbered parts of the drawings, our novel carburetor comprises the mixing chamber 5 and the float chamber or fuel reservoir 4, to which fuel is supplied through the intake 1, having an intake valve 2 therein controlled by the float 3, so as to maintain a uniform level of liquid in said float chamber. The float chamber 4 is disposed below the mixing chamber 5 and is connected thereto by means of a central stem 6, which passes through the center of the float chamber 4, and is screwed into the lower wall of the mixing chamber 5, the stem 6 being provided with a flange engaging the bottom of the float chamber so as to hold it in engagement with the mixing chamber 5 to hold the parts together. The stem 6 is tubular and is provided with an opening 8 in the side wall thereof, which is spaced a short distance above the bottom of the float chamber 4. A concentric tubular stem 10 is provided within the tubular stem 6, said stem 10 being provided with a ring groove 20, which has the shoulders 9 co-acting with the opening 8, to control the flow of fuel from the float chamber 4 into the nozzle, or, rather, into the interior of the tubular stem 6. The tubular stem 10

has a means 11 at its lower end whereby it may be adjusted within the tubular stem 6.

The primary nozzle 7 is screwed into the upper end of the tubular stem 6, as shown in Fig. 1, and said nozzle 7 is provided with the hollow extension 21, which is housed within the upper part of the tubular stem 6, and is provided with openings 22, 24 and 25. The upper end of the tubular stem 10 is housed within said hollow extension 21 and fuel may enter through the passage 8 in the side wall of the stem 6 into the chamber formed by the groove 20, and pass through the openings 22 into the chamber 19 between the extension 21 and the inner wall of the tubular stem 6. Air enters through the central passage in the tubular stem 10 and passes through the upper end thereof, and through the openings 24 into chamber 19 surrounding the extension 21, where it comes in contact with the fuel which has entered said chamber through the openings 22. The mixture of fuel and air thus formed passes through the openings 25 into the central passage 26 in the nozzle 7, through which it is drawn by the suction of the air passing through the mixing chamber 5. The secondary nozzle 18 is carried by said mixing chamber a short distance back of the primary nozzle, being somewhat shorter than said primary nozzle, and having its lower end extending into the float chamber 4, while its upper end extends into the mixing chamber at a point back of the primary nozzle 7.

The main air supply, which may be heated, if so desired, may enter the carbureter by the passage 12, which has the choke valve 13 therein, so that the main air supply may be cut off and the suction in the carbureter effective on the nozzle 7 correspondingly increased, so as to provide a rich mixture in starting the engine. The air supply passage, or section 12, is attached to the rear end of the mixing chamber 5, and a horizontally extending section, or cage, 14 is provided, which projects into the mixing chamber 5 and is secured thereto by removable means. The top and bottom walls of said cage are rigid, and the side walls of said passage are formed by the flexible reed members 15, consisting of leaf springs secured at the rear edges to the cage 14 by means of the screws 16. The forward edges 55 of said reeds are free so that the entire reed may flex and yield under the engine suction, so as to increase the cross section of the air passage at the nozzle. A butterfly valve 17 is provided for controlling the passage of the mixture from the carbureter to the engine.

The primary nozzle 7 extends through the bottom wall of the mixing chamber 5, into the air passage of said mixing chamber at the free ends of the flexible reed valves 15,

and between the same, as clearly appears from Figs. 2 and 5 of the drawing, and the secondary nozzle 18 extends into the air passage at a short distance in the rear of the primary nozzle 7, the said nozzle 18 extending through the bottom of the cage 14, as appears from Fig. 1 of the drawing. The cage 14 and the flexible reeds carried thereby constitute the choke tube section of the mixing chamber.

From the description of the parts given above, the operation of our structure should be very readily understood. Fuel enters the float chamber 4 through the intake 1 and the passage of said fuel into the float chamber is controlled by the valve 2 which is controlled by the float 3, so that a uniform level is maintained in the float chamber 4. The fuel is drawn from the float chamber 4 into the mixing chamber 5 of the carbureter 25 through the primary and secondary nozzles 7 and 18 respectively, the secondary nozzle coming into play as the engine suction increases.

The main air supply enters through the air supply passage 12 and passes through the mixing chamber 5, being directed through the cage 14 and between the flexible reeds 15, said cage and the flexible reeds forming a choke tube for the mixing chamber 5. Since the side walls of said choke tube are formed by the flexible reeds 15, it will be seen that the cross section of the said choke tube and the curve thereof is automatically variable depending upon the variation in the engine suction. The suction, which is exerted at the nozzle 7 upon the fuel, is dependent upon the cross section of the choke tube at that point, being dependent upon the velocity of the current of air flowing past that point, which is controlled by said cross section, so that the volume of air flowing past the nozzle and the suction exerted upon the fuel at the nozzle, which determines the amount of fuel fed from the nozzle, will both be automatically controlled by variations in the engine suction, so that, as the engine suction increases, the volume of air going past the nozzle will be increased and the cross section of the choke tube will be increased, so that there will be a corresponding decrease in the effective suction on the nozzle relative to the flow of air and more air will be supplied to the mixture and the fuel supplied to the air will not be increased to so great an extent, so as to provide a mixture which is too rich. As soon as the engine suction decreases, the internal flexibility and elasticity of the reeds will bring them back toward their normal position. In starting the engine, the choke valve 13 is used, so as to get a strong effective suction on the nozzle 7 to provide a rich mixture for starting. The secondary nozzle 18 is placed a short distance behind

the primary nozzle 7, and, as the engine suction increases, and the engine is speeded up, the secondary nozzle 18 will come into play so as to aid and assist the primary nozzle 7 in furnishing fuel for the air passing through the mixing chamber.

The nozzle 7 has an effective arrangement by means of which air may be admitted through the nozzle itself and mixed with the fuel before the fuel is delivered from the top of the nozzle to the current of air passing through the mixing chamber, and effective means are provided for adjusting the nozzle, so as to control the amount of fuel passing through it, and for mixing the air with fuel in the nozzle. Fuel enters through the passage 8 to the chamber formed between the inner wall of the tubular stem 6 and the ring 20 in the stem 10, and passes through the openings 22, in the extension 21, into the chamber 19, between the extension 21, and the inner wall of the tubular stem 6. Air enters through the tubular stem 10 and passes up through the upper end thereof, and out through the passages 24 into the chamber 19 between the extension 21 and the inner wall of the tubular stem 6. The air and fuel are mixed in this chamber and together pass out through the opening 25 and the passage 26, through the top of the nozzle 7, so that air and fuel are mixed together in the nozzle and delivered to the current of air passing through the mixing chamber 5 of the carburetor. The amount of fuel, which passes into the nozzle from the float chamber, may be effectively controlled by adjusting the tubular stem 10 so that the shoulder 9 thereon may vary the effective opening of the passage 8 to control the amount of fuel flowing therethrough.

We are aware that the particular embodiment of our invention, which we have here shown and described, is susceptible of considerable variation without departing from the spirit thereof, but we have found that this particular embodiment is desirable from many standpoints, and, therefore, we desire to claim the same specifically, as well as broadly, as indicated by the appended claims.

Having thus described our invention, what we claim as new and desire to secure by Letters Patent, is:

1. In a carburetor, the combination with a fuel supply nozzle, of an air supply passage, a valve comprising a plurality of leaf springs mounted in said passage so that the nozzle is adjacent the greatest movement of the leaf springs and extends transversely of the air supply passage to substantially close said passage when the springs are in their normal position.

2. In a device of the class described, the combination with a fuel supply nozzle, of

an air supply passage, a choke tube section therein comprising a frame having a plurality of triangular shaped sides and a plurality of rectangular sides, and flexible reeds normally closing openings in certain of said sides.

3. In a carburetor, in combination with a main air supply passage, a fuel nozzle projecting into said air supply passage, and a valve comprising oppositely positioned converging flexible reeds having their free ends located adjacent the fuel nozzle and normally co-operating therewith to substantially close said main air supply passage.

4. A device of the class described, comprising the combination of a mixing chamber; a fuel reservoir; a choke tube having side walls formed of flexible reeds adapted to yield under suction to increase the cross section of said choke tube; a primary fuel nozzle extending between the free ends of said reeds, and a secondary nozzle projecting into said choke tube in the rear of said primary nozzle.

5. A device of the class described, comprising the combination of a mixing chamber; a fuel reservoir; a removable choke tube section having side walls formed of converging flexible reeds secured at the rear edges to said section; a primary nozzle projecting into said mixing chamber between the free end of said reeds, and a secondary nozzle projecting into said section behind said primary nozzle.

6. A device of the class described, comprising the combination of a mixing chamber; a fuel reservoir; a tubular stem extending centrally through said fuel reservoir and threaded into the wall of said mixing chamber, and securing said reservoir to said mixing chamber; a nozzle carried by said stem and projecting into said mixing chamber; a tubular member threaded within the stem and projecting within a tubular opening in the lower end of the nozzle; and connections between said nozzle and said fuel reservoir.

7. A device of the class described, comprising the combination of a mixing chamber; a fuel reservoir; a tubular stem connecting said reservoir and said mixing chamber and securing the one to the other; a nozzle carried by said stem and projecting into said mixing chamber; a tubular member threaded within the stem and projecting within a tubular opening in the lower end of the nozzle; and connections between said nozzle and said reservoir.

8. A device of the class described, comprising the combination of a mixing chamber; a fuel reservoir; a central stem disposed in said reservoir and provided with a passage through the side wall thereof; a nozzle threaded into the upper end of said central stem, said nozzle being provided

with an extension on the lower end thereof disposed within said central stem; a chamber provided between said extension and the inner wall of said central stem; a longitudinally extending passage in the upper part of said nozzle; a passage connecting said longitudinal passage with the chamber in said stem; a chamber formed in the lower part of said extension; passages connecting said chamber with the chamber between said extension and said central stem; and an adjustable tubular stem disposed within said central stem, and within the chamber of said nozzle extension, said tubular stem having a ring groove formed therein; and means for adjusting said tubular stem in said central stem.

9. A device of the class described, comprising the combination of a mixing chamber; a fuel reservoir; a hollow central stem disposed in said reservoir, and having a passage connecting with the interior of said central stem; a nozzle carried by said central stem and having an extension disposed within the interior of said central stem, said nozzle having a passage in the upper part thereof connected with the chamber between said extension and the central stem; and a longitudinally extending tubular stem disposed within the chamber formed within said extension of said nozzle, and adjustable therein, said extension being provided with openings in the side thereof, connecting said nozzle extension chamber with the chamber in said central stem; an annular shoulder on said longitudinally adjustable tubular stem, dividing the chamber in said nozzle extension into two parts, the upper part communicating through the central opening in said tubular stem with the air, and the lower part communicating through the passage in the side wall of the central stem with the fuel reservoir; and means for adjusting said tubular stem in said nozzle extension.

10. A device of the class described, comprising the combination of a mixing chamber; a fuel reservoir; a central stem disposed in said float chamber and provided with a central chamber therein; a passage connecting said central chamber with the float chamber; a nozzle extension disposed in said chamber; a passage in the upper part of said nozzle connected with said chamber; a stem adjustable in said chamber, and having its upper part disposed in a chamber provided in said nozzle extension; means for adjusting said stem to control the passage of fuel from said float chamber to said first-mentioned chamber; and connections between said chamber and the atmosphere through the axial opening in said tubular adjustable stem.

11. In a device of the class described, a mixing chamber, a primary fuel supply nozzle,

79
zle, a choke tube section comprising converging leaf springs, and a secondary fuel supply nozzle opening into the choke tube section in the rear of the primary fuel supply nozzle.

12. In a device of the class described, the combination with a fuel supply pipe, of a choke tube comprising a frame provided with triangular portions symmetrically positioned relatively to each other, and flexible reeds each secured at one end to the frame and adapted to seat against the edges of the triangular portions.

13. In a device of the class described, the combination with a fuel supply pipe, of a choke tube comprising a frame provided with triangular portions symmetrically positioned relatively to each other, and side portions each of which is flexibly secured at one end to the frame and adapted to seat against the edges of the triangular frame portions.

14. In a device of the class described, a fuel nozzle provided with radial openings for admitting a mixture of air and fuel thereto, a member having a chamber communicating with said radial openings, and independent air and fuel passages to said chamber.

15. In a device of the class described, a fuel reservoir, a mixing chamber, and means for feeding fuel from the fuel reservoir to the mixing chamber comprising an outer tubular member, a fuel nozzle positioned within the tubular member, and a second tubular member positioned within the first-named tubular member and manually adjustable therein to control the supply of fuel to the fuel nozzle.

16. In a device of the class described, a fuel reservoir, a mixing chamber, and means for feeding fuel from the fuel reservoir to the mixing chamber comprising an outer tubular member, and a fuel nozzle positioned within the tubular member and provided with tubular end portions having radial openings for placing the tubular end portions of the nozzle in communication with the interior of the tubular member.

17. In a device of the class described, a fuel nozzle provided with separate longitudinal openings formed in its opposite ends, and radial passages extending outwardly from the longitudinal openings, an annular chamber communicating with certain of the radial passages whereby air and fuel may be intermingled in the annular chamber and the fuel mixture thus formed supplied to one of the longitudinal openings of the fuel nozzle.

18. In a device of the class described, the combination of a reservoir, a mixing chamber, a tube secured to the mixing chamber and extending into the reservoir, said tube being in communication with the reservoir, a nozzle projecting into one end of said tube

and communicating therewith, and an air inlet tube projecting into the opposite end of said first mentioned tube and communicating with said nozzle.

5 19. In a device of the class described, the combination of a reservoir, a tube extending into the reservoir and in communication therewith, a nozzle extending into said tube in communication therewith, and an air inlet tube extending into said first mentioned tube and projecting into said nozzle and communicating with the first mentioned tube through apertures in said nozzle.

10 20. In a device of the class described, a fuel reservoir, a mixing chamber, and a fuel nozzle provided with separate longitudinal openings formed in opposite ends thereof, and a plurality of radial passages communicating with one of said longitudinal openings.

15 21. In a device of the class described, a fuel reservoir, a mixing chamber, a fuel nozzle provided with separate longitudinal openings formed in the opposite ends thereof, a plurality of radial passages communicating with one of said longitudinal openings, and a tubular member having one end portion projecting within the longitudinal opening formed in one end of the nozzle.

20 22. In a carbureter, a fuel reservoir, a mixing chamber, a tubular structure extending

through the reservoir and provided with passages for admitting air to one end of the tubular structure and liquid fuel intermediate the ends thereof and for discharging 30 a mixture of air and fuel from the opposite end of said tubular structure.

23. In a device of the class described, the combination with a fuel reservoir, a mixing chamber, a tubular structure extending 40 through said reservoir having longitudinally extending passages therein communicating with the atmosphere and with said mixing chamber, said passages being adapted to receive fuel from said reservoir which is adapted to mix with air fed through said passages.

24. In a carbureter, a mixing chamber, a fuel reservoir, a tubular member extending from the mixing chamber into the fuel reservoir, and a pair of tubular members mounted in the first named tubular member one of which is telescoped within the other, said last named tubular member being provided with passages communicating with the atmosphere and with the fuel reservoir for 55 supplying a mixture of air and fuel to the mixing chamber.

In testimony whereof we affix our signatures.

GEORGE F. RITTER.
HARRY C. TILLOTSON.
